[57] **CLAIM**

The ornamental design for a housing for a two-way radio repeater, as shown and described.

DESCRIPTION

FIG. 1 is an isometric view of a housing for a two-way radio repeater showing our new design;

FIG. 2 is a front view thereof;

FIG. 3 is a left side view thereof;

FIG. 4 is a right side view thereof;

FIG. 5 is a top plan view thereof; and,

FIG. 6 is a bottom plan view thereof.

The broken lines shown in FIGS. 1-6 are included for the purpose of illustrating environmental elements only and forms no part of the claimed design.
